UNITED STATES PATENT OFFICE.

HIRAM G. SEDGWICK, OF MILL VALLEY, CALIFORNIA.

TRAIN-STOPPING APPARATUS.

No. 852,633.

Specification of Letters Patent.

Patented May 7, 1907.

Application filed June 14, 1906. Serial No. 321,763.

To all whom it may concern:

Be it known that I, HIRAM G. SEDGWICK, a citizen of the United States of America, and a resident of Mill Valley, county of Marin, 5 State of California, have invented certain new and useful Improvements in Train-Stopping Apparatus, of which the following is a full and clear specification, reference being had to the accompanying drawings, in 10 which—

Figure 1 is a diagrammatic view of, one block showing the arrangement of contacts and roadbed circuits, the signal devices at the head of the block being omitted; Fig. 2 a 15 similar view showing one end of the block and the signal devices connected thereto; Fig. 3 a detail perspective view showing the motor circuits and cam device for raising the semaphore to danger; Fig. 4 is a view 20 showing a modified arrangement of the signal devices.

The object of this invention is to provide an extremely simple block system for preventing collisions, means being provided 25 whereby each train as it proceeds preëmpts a block or section of the roadway, preventing any train coming from either direction from entering the block until it is free of trains, the means for preventing trains from entering the block while thus preëmpted being entirely automatic and independent of all signals and the actions of the train-crews, as 30 more fully hereinafter set forth.

To the accomplishment of this object and 35 such others as may hereinafter appear, the invention consists of the parts and combination of parts hereinafter fully described, and particularly pointed out in the appended claims, reference being had to the accompanying drawings forming a part of this 40 specification, in which the same reference-characters designate like parts throughout the several views.

This invention has special reference to the 45 train-stopping system covered by my pending application No. 288,914, filed November 24, 1905.

One object of the present invention is to do away with the setting-contacts and the 50 store-contacts and to use in lieu thereof short insulated sections of the track rails, and another object is to provide that system with automatic signal devices, as more fully hereinafter set forth.

55 This system like the system set forth in my

aforesaid application is adapted to be used in connection with contacts or brushes carried by the locomotive or motor car, the locomotive being provided with a local circuit or circuits whereby when the brushes are 60 bridged or metallically connected by the stopping-contacts on the roadbed, the train pipe will be vented and the brakes applied or other suitable train-stopping devices put into operation. In the present system the brake 65 magnet is operated by means of a battery on the locomotive thereby doing away with numerous local batteries on the roadbed, and the locomotive is provided with duplicate pairs of brushes on each side and with means 70 for cutting in one pair of brushes and cutting out the other pair when the engine is reversed, so that the locomotive brushes will coact only with the contacts on the right side of the track looking in the direction in which 75 the train is moving and whether or not the locomotive be going forward or backward.

In the present system the stopping-contacts a' are arranged, as formerly, at each end of the block and on opposite sides of the 80 track and a short distance ahead of each pair of contacts is a pair of short rail sections b' which are adapted to be electrically connected by the wheels and axles of the trains and which are adapted to set the stopping-contacts. 85 The restore sections c' of the rails are located between the stopping devices on the setting rail sections b' , so that a train before entering a block will pass over successively the stopping-contacts, the restore rail sections c' , and then the setting rails b' , and on 90 leaving a block a train passes over the rail sections in the reverse order. It will be understood that the restore rail sections c' are arranged at the end of each block while the 95 setting rail sections are adapted to operate only as a train enters a block. It will be understood also that the stopping-contacts a' at one end of the block are adapted to co-operate only with trains going in one direction while the contacts at the other end of the block are reversely arranged in that they are adapted to co-operate only with trains 100 going in the opposite direction.

At the beginning of each block is conveniently placed a relay or switch box d' preferably mounted on the usual telegraph poles adjacent to the roadbed and these boxes are connected by two line wires e', f' . The restore rails c' at the end of a block and also 105

the stopping-contacts a' and the setting rails b' at the beginning of the same block are connected by wires to the adjacent relay box.

- The stopping-contacts are connected by 5 wires g' to a switch h' which is adapted to be closed by a magnet j' and to be opened by a magnet k' . When the switch h' is closed the stopping-contacts are metallically connected and when the switch is open these contacts 10 are rendered inactive, as is obvious. The setting rail sections b' are connected by wires l' to a battery m' , one limb of the circuit passing through the magnet of a switch n' , this switch being preferably the ordinary 15 telegraph sounder and having its lower contact connected to ground through a battery o' and its upper contact connected to ground through a wire p' . The armature lever of this switch, which normally bears up against 20 the upper contact is connected by a wire q' with switch r' , this switch being preferably the ordinary relay circuit-closer used in telegraphy. The wire q' passes through the 25 magnets of this relay and becomes the line wire f' , which leads to the relay box at the other end of the block and connects with the companion relay r' in that box. The relay r' when energized closes the circuit t' of the 30 closing magnet j' , the wires of this circuit being connected to the aforesaid battery m' .

In each relay box d' the above described mechanism is duplicated, the opening magnet k' being connected by wires u' to a relay v' and a battery w' , and one of the wires x' of 35 this relay being connected through the armature lever of a switch y' and a wire z' to ground, while the other wire a^2 of this relay goes out of the box and becomes the line wire e' leading to the companion relay v' at the 40 other end of the block. The magnet of the sounder switch y' is connected in circuit with battery w' by the wires b^2 with the restore rail sections c' . The lower contact of each 45 of the switches y' is connected to ground through a battery c^2 .

One limb of each of the circuits b^2 has inserted in it a circuit breaker b^3 consisting of a stationary contact and a movable contact mounted on the armature lever of the 50 sounder switch n' , so that when the sounder switch is energized the circuit b^2 will be broken at b^3 .

With an arrangement such as described, it 55 will be observed that if switch h' is closed and the stopping-contacts thereby bridged, a locomotive upon approaching the beginning of a block will be automatically stopped as soon as its contact brushes strike the stopping-contacts. Should the stopping-contacts 60 be inactive the train will be permitted to pass along and bridge or connect all the rail-contacts in succession. The first pair of wheels of the train that strikes the restore rail-contacts c' will close circuit b^2 and draw 65 down the armature of switch y' thereby send-

ing the current of battery c^2 up through relay v' and to line e' . In passing through relay v' circuit u' will be closed and magnet k' thereby energized but inasmuch as switch h' is already open no disturbance of the arrangement of parts will occur; and as the current passes on through the relay v' in the box at the other end of the block the same result will take place as the magnet circuit in that box is also open; this bridging of the contacts therefore performs no useful function nor does it disarrange any of the circuit arrangements.

When the wheels strike the contacts b' circuit l' is closed thereby energizing the 80 magnet in switch n' which draws down the armature lever thereof thus breaking contact b^3 and opening circuit b^2 , the result of this being to put out of action the restore-contacts c' and thereby prevent the intermittent making and breaking of the circuit b^2 , this repeated making and breaking of circuit b^2 being objectionable in that it would soon wear out and disarrange the switch y' by racking it. The contact-rails b' are desirably made long enough to prevent the circuit l' being broken again until the entire train passes off these rail sections. The bridging of the contacts b' sends a current from battery o' through wire q' and relay r' to line f' , thus closing circuit t' and energizing magnet j' from battery m' , which closes switch h' and renders the stopping-contacts a' active; the current passes on through line f' to the relay box at the other end of the block and there performs the same operations as in the first box, thereby closing the other switch h' and rendering the stopping-contacts on the other side of the roadbed active and thus guarding the block 95 against trains coming into it from the opposite direction.

At the end of the block the train passes over setting-contacts b' but does not disarrange any of the circuits as the switches h' are closed and the energizing of the magnet in switch n' in this latter box simply repeats the operations which were performed when the train previously passed over the setting-contacts at the beginning of the same block. After the last pair of wheels have passed off these setting contact rails the restore-contacts c' at the end of the block are permitted to act thus restoring all the parts to normal and rendering both stopping-contacts inactive. This restoring action takes place by closing circuit b^2 which, as before described, sends a current from battery c^2 up through relay v' (thus energizing magnet k' and opening switch h') and thence backward through line e' so as to perform the same operations in the box at the other end of the block.

It will thus be observed that by the arrangement of switches and circuits above 130

set forth I am enabled to employ as setting and restoring contacts insulated sections of the railway rails, thereby avoiding the necessity of employing separate contacts on the roadbed along side the rails and also avoiding the use of additional pairs of brushes for performing the setting and restoring operations, the wheels of the trains serving as brushes.

10 I may employ any suitable audible or visual signal arrangements with the present system, but I prefer the signaling arrangement shown. In my present arrangement I mount on a suitable pole at each end of 15 the block a semaphore 2, which when at danger, as shown in Fig. 2, which is its normal position, closes a circuit 3 by means of contacts 4, said circuit being connected with the stopping-contacts at the same end of the 20 block, thereby rendering said contacts active so that a train cannot enter the block without first lowering the semaphore to safety and thus break the circuit 3. The semaphore is dropped to safety by means of 25 a pair of rail-contacts 5 insulated from the main rails and located a suitable distance from the stopping-contacts in the adjacent block. Connected to these signal contact rails is a circuit 6 included in which is a battery 7 and a 30 magnet 8 and which is adapted to be opened and closed at switch h' in the relay box at the adjacent end of the block, a suitable contact 9 being arranged to close this circuit when said switch is open and the stopping-contacts 35 are inactive. When said switch h' is closed to render the stopping-contacts at the head of the block active said circuit 6 is broken at 9 so that the passage of a train over contacts 5 will not energize magnet 8. 40 Should the switch h' be open and the block thus be clear the energizing of magnet 8 will withdraw spring-actuated bolt 10 from under a rod 11 connected at its upper end to the semaphore, thus permitting the rod and 45 the semaphore to drop to safety and indicate to the engineer that the block is clear and at the same time break circuit 3 and permit the train to pass into the block.

When the rod 11 drops it rests upon the 50 cam 12 mounted upon a shaft 13 which is suitably geared to an electric motor 14. As the train passes over the setting-contacts b' and closes circuit b' it also brings contacts 55 together and closes a circuit 16 which includes a battery 17, a pair of spring contacts 18 and the motor 14, thus causing the motor to be brought into operation to rotate cam 12 in the direction of the arrow. The contacts 18 rest upon and are electrically connected by a semi-circular contact 19 carried 60 insulatedly on the cam shaft. When the cam shaft has rotated in the direction of the arrow a half revolution the contacts 18 drop off the end of the circuit-closing contact 19 thereby breaking circuit 16 and stopping the

motor. This half turn of the shaft raises rod 11 and permits spring-actuated bolt 10 to snap under it and thereby hold it up until it is again dropped by the energizing of the magnet 8. When the cam is in this position 70 its enlarged or semi-circular part will be directly under the semaphore rod, so that it will be impossible for an oncoming train to drop the semaphore to safety, thus providing an additional safeguard against an oncoming 75 train entering the block. The parts remain in this position until the train reaches the end of the block when it passes over the restore-contacts at that end and opens both switches h' thus opening circuit 16 and closing another motor circuit 20 at contacts 21. This motor circuit includes a battery 22, a pair of spring contacts 23 similar to contacts 18, and the motor 14, and thus again rotates 80 the motor in the same direction. The contact fingers 23 bear upon a semi-circular circuit-closing contact 24 similar to contact 19 and mounted insulatedly on the cam shaft, this contact 24 being so located that when contact fingers 18 drop off contact 19 these 85 fingers 23 pass into their own contact 24 thus completing motor circuit 20 at this point. It will thus be observed that when circuit 20 is thus closed at 24 and at 21 the motor will be caused to make another half turn of shaft 13 90 and then be stopped by the fingers 23 dropping off of the other end of contact 24. This half turn of the cam is an idle one and is simply for the purpose of carrying the straight shoulder of the cam around to the position shown 95 in Fig. 1 where the enlarged part of the cam will not interfere with the dropping of the semaphore rod. This position of the cam is therefore the normal or safety position, the cam being brought to this position every time 100 a train passes over the restore-contacts at the end of the block. It will be understood of course that the same operations take place at the same instant at both ends of the block and that the operations take place in the reverse order when a train passes through the block in a reverse direction, so that these signal devices provide an additional safeguard 105 against the entrance of a train into a block while that block is preempted by another 110 train going in either direction thereon. These signal devices of course will be placed at such a distance ahead of each block as to enable a train to be stopped before it enters a preempted block, and, if desired, suitable 115 lamp or other supplemental signals may be arranged to indicate to the blocked train-crew in which direction the train in the block is going, so that the blocked train-crews will know whether to stop and back or to go 120 ahead slowly.

In Fig. 4 a modified arrangement of the signal devices is shown. In this arrangement when the semaphore drops it not only opens the circuit 3 but closes a circuit 25 at con- 130

acts 26, in which circuit is included a suitable battery which is connected to the motor 14 and thereby operates said motor to instantly raise the semaphore to danger. In this arrangement the circuits 16 and 20 are done away with but the signal circuit 6 remains as before, so that if the block is preempted the circuit 6 cannot be closed and the semaphore cannot be dropped to safety. But if circuit 6 is closed the semaphore will be dropped and will instantly begin to rise through the motor, the motor continuing to rotate until the raising of the semaphore breaks the motor circuit at 26, by which time the semaphore rod 11 will have been elevated far enough to permit bolt 10 to slip under the lower end of the rod and thus hold up the semaphore. In this arrangement, therefore, the semaphore is restored independently of the restore-contacts, and it will also be understood that in this arrangement the signal will be located close enough to the stopping-contacts, if circuit 3 be employed at all, to permit the train to pass over the stopping-contacts before the circuit 3 is closed again at 4.

It will be apparent to those skilled in the art that various mechanical embodiments of the invention are possible and I, therefore, do not wish to be limited to the exact arrangement and construction shown.

What I claim and desire to secure by Letters Patent is:—

1. In an apparatus of the class set forth, a block having stopping devices at each end thereof and at opposite sides of the track, a pair of insulated setting rail-contacts at each end of the block inside of the stopping devices, a pair of restore rail-contacts between each pair of setting-contacts and the adjacent stopping devices, the stopping devices being arranged to co-operate with stopping means on the locomotive and the rail-contacts being adapted to be bridged by the wheels and axles of the trains, and electrical connections whereby the bridging of either pair of setting-contacts will set both the stopping devices and the bridging of either pair of restore-contacts will restore both the stopping devices to safety, substantially as set forth.

2. In an apparatus of the class set forth, a block having stopping devices at each end thereof and at opposite sides of the track, a pair of insulated setting rail-contacts at each end of the block inside of the stopping devices, a pair of restore rail-contacts between each pair of setting-contacts and the adjacent stopping devices, the stopping devices being arranged to co-operate with stopping means on the locomotive and the rail-contacts being adapted to be bridged by the wheels and axles of the trains, and electrical connections whereby the bridging of either pair of setting-contacts will set both the stopping devices to safety, substantially as set forth.

stopping devices and the bridging of either pair of restore-contacts will restore both the stopping devices to safety, these electrical connections including means whereby the bridging of the restore-contacts at the head of the block will be prevented from setting the stopping devices.

3. In an apparatus of the class set forth, a block having stopping devices at each end thereof and at opposite sides of the track, a pair of insulated setting rail-contacts at each end of the block inside of the stopping devices, a pair of restore rail-contacts between each pair of setting-contacts and the adjacent stopping devices, the stopping devices being arranged to co-operate with stopping means on the locomotive and the rail-contacts being adapted to be bridged by the wheels and axles of the trains, and electrical connections whereby the bridging of either pair of setting-contacts will set both the stopping devices and the bridging of either pair of restore-contacts will restore both the stopping devices to safety, said electrical connections including means whereby the passage of a train over the restore-contacts at the head of the block will be prevented from disarranging any of the circuits.

4. In combination with a train-stopping block system embodying stopping, setting and restoring devices on the roadbed, of a signal appliance normally held at danger, and electrical means whereby a train approaching the block will bring said signal to safety if the block be free and then be restored to danger as the train enters the block.

5. In combination with a train-stopping system embodying a block and electrically-controlled means for preempting the block by the entrance of a train therein, of a signal appliance at each end of the block and means for maintaining it normally at danger, means outside of each end of the block for bringing said signal to safety if the block be not preempted, and means whereby the signal will be restored to danger upon the entrance of the train into the block and be locked at danger while the train is in the block and be left at danger when the train passes out of the block.

6. In an apparatus of the class set forth, a block having stopping devices at each end thereof, a pair of insulated setting rail-contacts at each end of the block inside of the stopping devices, a pair of restore rail-contacts, the stopping devices being arranged to co-operate with stopping means on the locomotive and the rail-contacts being adapted to be electrically bridged by the wheels and axles of the trains, and electrical connections whereby the bridging of either pair of setting-contacts will set both the stopping devices to danger and the bringing of either pair of restore-contacts will restore both the stopping devices to safety, substantially as set forth.

7. In an apparatus of the class set forth, a block having stopping devices at each end thereof, a pair of insulated setting rail-contacts at each end of the block inside of the 5 stopping devices, a pair of restore rail-contacts ahead of or outside each pair of setting-contacts, the stopping devices being arranged to co-operate with stopping means on the locomotive and the rail-contacts being adapted to be bridged by the wheels and axles of the trains, and electrical connections whereby the bridging of either pair of setting-contacts will set both the stopping devices to danger and the bridging of either pair of 10 restore-contacts will restore both the stopping devices to safety, these electrical connections including means whereby the bridging of the restore-contacts at the head of the 15 block will be prevented from setting the stopping devices.
8. In combination with a train-stopping system embodying stopping devices and an electrical circuit therefor which is normally open, and means for rendering the stopping 20 devices active when the block is preempted, 25
- of a signal appliance normally held at danger and connected to stopping devices to hold them normally at danger, and electrical means whereby a train approaching the block will bring said signal to safety if the block be 30 free and be returned to danger and held there while the block is occupied.
9. In combination with a train-stopping block system embodying stopping devices on the roadbed and means whereby these stopping devices are rendered active when the block is occupied, a signal and electrical means operable by an approaching train and connected to the stopping system whereby the signal is moved to safety as a train enters 35 the block if the block be unoccupied and be restored to danger and held there while the block is occupied.

In testimony whereof I hereunto affix my signature in the presence of two witnesses 40 this 7th day of April 1906.

HIRAM G. SEDGWICK.
